UNITED STATES PATENT OFFICE.

JOSEPH L. GOLDIE, OF SYRACUSE, NEW YORK, ASSIGNOR, BY MESNE ASSIGNMENTS, TO KLEEN KAP CORPORATION, OF SYRACUSE, NEW YORK, A CORPORATION OF NEW YORK.

BOTTLE-CAPPING MACHINE.

Application filed August 22, 1927. Serial No. 214,731.

This invention relates to mechanical means for applying closures to the mouths of milk and other bottles, and has for its object to provide novel power actuated means for automatically handling disc-shaped bottle caps that are formed with peripheral tabs or lugs by which the caps are removed from the bottles. A further object is to provide a combined carton and magazine, in which the closures may be packed at the manufactory, and from which they may be fed singly into the capping machine, without requiring rehandling of the closures. The said carton being split longitudinally throughout the length of its body and the facing margins of the slot being formed into external parallel flanges which receive, align and guide the projecting pull-lugs. A further object is to provide a corresponding rearwardly facing vertical slot in the usual cylindrical cap containers with which the ordinary capping machines are fitted to receive and guide the protruding flanges of the carton. A further object is to provide a shuttle-like member for delivering the lowermost closure of the stack supported by the magazine or carton, to the capping position, by the release stroke of the capping plunger, said shuttle having a recess that faces the coinciding slots of the carton and permanent cap-container which receives the protruding pull-tabs, and by which the closures are delivered to the capping chamber without danger of the tabs shifting and interfering with the feeding or capping operation. And a further object is to so modify certain parts of a well-known capping machine that my invention may be applied without requiring any extra parts except the substitution of the split cylindrical carton for the ordinary cap-container, referred to.

I attain these objects by the means set forth in the detailed description which follows, and as illustrated by the accompanying drawing, in which—

Figure 1 is a top plan view of a bottle capping machine, the cap applying parts being in the operative position, and the cap feeding parts being in the released position. Fig. 2 is a partial side elevation, and partial central vertical longitudinal section, taken on line 2—2 of Fig. 1, showing the capping and feeding parts in positions corresponding to Fig. 1. Fig. 3 is a hori-

zontal section, taken on line 3—3 of Fig. 2, showing the shuttle in the act of depositing a cap in the path of the plunger, the latter being released, corresponding to the dotted positions of Figs. 2 and 4. Fig. 4 is a broken side elevation taken in the direction of the arrow in Fig. 3. Fig. 5 is an end elevation of the fibrous carton. Fig. 5^a is a side elevation of the carton. And Fig. 6 is a plan view of one of the closures.

In the drawing, 2 represents the body of a bottle capping machine, commonly employed for applying plain disc-shaped caps or closures (not shown), which is formed with an upright cylindrical chamber 2', whose open bottom is formed bell-shaped to receive and center the mouth-end of an ordinary milk bottle, as A. The power-driven capping member comprises a rod 3, which reciprocates in a way 3' formed in the body 2 concentric to chamber 2', the lower end of the plunger 3 comprising a disc-shaped head 3^a, which seats the closures in the bottle mouth. Rearwardly of the chamber 2' is disposed the usual relatively short cylindrical container 4 for the plain disc-closures, whose axis parallels the axis of chamber 2'. The top and bottom ends of the part 4 are normally open, so that the closures ordinarily gravitate to the feeding position. The caps are moved forwardly horizontally from the container 4 in a plane slightly higher than the seat *a* of the bottle mouth, by a shuttle-like member 5, that moves frictionally over a plane bed 2^a, which corresponds to the top surface of a rearwardly extending guide-arm 2^d, and beneath a spring-guard *x* that projects rearwardly beyond the container 4, and exerts the requisite tension for holding member 5 against the bed. The member 5 is mounted between and operated by the long arms 6 of similar L-shaped levers which are pivoted to a horizontally movable part 5' that slidably engages the opposite edges of the guide 2^d. The levers 6 are pivoted to the opposite sides of the magazine 4 by pins 6', and their short arms 6^a are connected by links 6^b, to a yoke 6^c, whose stem 6^d is rigid to and movable vertically with the plunger 3. By this arrangement, the shuttle 5 is moved forwardly and backwardly when the levers 6 are rocked by reciprocation of the plunger 3, as may be understood by comparing Figs. 1 and 2 with Figs. 3 and 4, and each forward

stroke of the shuttle 5 carries the lowermost cap, as 7, from the magazine 4 towards the chamber 2' to be driven downwardly into the bottle-mouth by the down stroke of the head 5 3^a (see Fig. 2), which simultaneously moves the shuttle rearwardly in position to feed the next cap 7, and so on.

The present invention relates to automatic means for feeding the disc-shaped caps 7, 10 that are formed with protruding peripheral pull-lugs, as 7', which heretofore, so far as I am aware, have been invariably applied to the bottle mouths by hand. To this end, my invention includes first, the forming of 15 the permanent magazine 4, with a relatively broad vertical rearwardly facing slot or opening 4' (see Fig. 1), that preferably extends the full length of said magazine, through which the pull-lugs 7' project, as 20 best seen in Figs. 1 and 2. The slot 4' is preferably of such breadth that, the lugs 7' are practically free, and therefore the caps readily gravitate toward the feeding plane 2^c. In order to enable the tabs 7' to reach 25 the level of the bed 2^c, the spring-guard α is cut away as at α' (see Figs. 1 and 3). The shuttle 5 is usually formed with a forwardly facing concave margin 5^a, that substantially, though rather loosely, conforms 30 to the normal curvature of the caps 7 and insures the direct forward feeding of the caps. By disposing the lugs 7', as herein shown and described, it becomes necessary to provide the member 5 with a recess or notch, 35 as 5^b, that preferably coincides with the longitudinal center of said member, and intersects the concave margin 5^a (see Figs. 1 and 3), to receive the said lug and prevent the miscarriage or accidental shifting of the 40 cap during its travel from the magazine toward the capping chamber 2'. This arrangement insures such positive positioning of the caps in chamber 2' that the lugs 7' always face rearwardly, and when a cap 45 enters the said chamber its forward plain portion 7^a tends to gravitate slightly, while the lug 7' lodges against the rear wall of the contracted bore 2^f, of the chamber 2'. This frees the lug 7' from the narrow horizontal way indicated at 2^x (see Figs. 2 and 4) and enables the head 3' to depress the cap and effect the proper closing of the bottle-mouth, as shown in Fig. 2. This latter operation is facilitated by the smaller 50 diameter of the bore 2^f being slightly less

than the diameter of the disc 7, which prevents the cap from gravitating into the mouth of the bottle.

A particular object of the present invention is to provide an elongated carton, as 8, 60 of novel construction, in which 500 or more of the closures 7 may be packed or stacked by the manufacturer, the said carton preferably comprising an elongated fibrous cylinder such as card-board having a longitudinal 65 slot 8' extending from end to end, the opposing margins of said slot being rolled or formed into outwardly projecting flanges, as 8^a (see Fig. 5) which receive, protect, and 70 guide the tabs 7' of the closures, as shown in Figs. 1, 2 and 3. The span of the flanges 8^a is preferably substantially equal to the breadth of the slot 4' of the magazine portion 4, and facilitates the insertion of the 75 loaded carton into the said portion, for accurately positioning the closures 7 for the proper feeding of the latter, as explained. By this construction and arrangement, the loaded carton 8, may be readily and quickly 80 applied to the capping machine, thereby obviating the necessity of unloading, or transferring the closures in small lots from the carton to the relatively short magazine 4. The opposite ends of the carton 8 are normally open, the same as the cylinder 4, and 85 for the purpose of transporting the cartons 8, the latter may be simply wrapped like any ordinary package, and only the wrappers need be removed, in order to prepare the 90 tube 8 for immediate application to the machine, as shown in Figs. 1 and 2. The carton-magazines 8 may be provided at small cost, and when emptied may be discarded like the wrappers.

Having thus described my invention, what 95 I claim, is—

A bottle capping machine including a member having bottle mouth engaging means and a bed thereabove, a slide on the bed having an opening formed to receive 100 caps having peripheral pull-tabs, means to operate the slide, a container for the caps having a slot in its sides through which the pull-tabs extend, and a spring guard adjacent the container engaging the slide to 105 hold same against the bed and formed with a cut-away part registering with the container slot to receive the tabs.

In testimony whereof I affix my signature.
JOSEPH L. GOLDFIE
